UNITED STATES PATENT OFFICE.

LAWRENCE Y. SPEAR, OF GROTON, CONNECTICUT, ASSIGNOR TO ELECTRIC BOAT COMPANY, OF NEW YORK, N. Y., A CORPORATION OF NEW JERSEY.

HATCH STRUCTURE FOR SUBMARINES.

1,271,381.

Specification of Letters Patent.

Patented July 2, 1918.

Application filed January 7, 1916. Serial No. 70,746.

To all whom it may concern:

Be it known that I, LAWRENCE Y. SPEAR, a citizen of the United States, and a resident of Groton, in the county of New London and State of Connecticut, have invented certain new and useful Improvements in Hatch Structures for Submarines, and I do hereby declare the following to be a full, clear, and exact description of the invention, such as will enable others skilled in the art to which it appertains to make and use the same.

This invention relates broadly to submarine boats and more particularly discloses a construction which could advantageously be employed in connection with a rendezvous, storage, or "base" for a submarine. I shall hereinafter refer to such a vessel as a mother-submarine.

The provision of such a mother-submarine is surrounded with many problems not heretofore solved in a practical manner, one of the most important of which is the provision of storage and handling means for taking care of torpedoes (or any one of several bodies whose length is comparatively great compared to its maximum lateral dimension) to be transferred at intervals to a roving and fighting submarine periodically or whenever possible returning to its base as established by the mother-submarine. A submarine thus returning to the mother-submarine for new supplies I shall hereinafter refer to as a daughter-submarine.

In such a mother-submarine, on account of the shape of the vessel and the living, operating and machinery compartments necessarily present it is impractical to make the torpedo storage compartment of a height such that the torpedo may be arranged vertically therein. And if the compartment is not of such height, the torpedo may not be withdrawn through a horizontally arranged hatch located above the compartment unless such hatch, if round, be of an impractical diameter, having regard to the beam of the vessel. If, in these circumstances, a round hatch is sought to be avoided by the provision of an elongated hatch, the obstacles to a water-tight closure are greatly multiplied.

The problem above described is solved in accordance with the present invention, by providing above the torpedo storage or handling compartment, a vestibule or minor-

compartment, preferably tapering in form, directly over the torpedo compartment; in combination with an elongated hatch between the torpedo compartment and the minor compartment and a preferably circular hatch at the top of the minor compartment. The elongated hatch is preferably provided with a hatch cover for making a spray-tight closure, and the circular hatch is preferably provided with the tested, accepted and ordinary type of hatch cover for adjustment quickly to make a watertight closure of such circular hatch.

In the accompanying drawing, which shows the preferred embodiment of the present invention,

Figure 1 is a sectional view showing a part of a mother-submarine equipped with said embodiment; and

Fig. 2 is a top plan detail view, partly broken away.

The numerals 3 and 4 represent respectively the hull and superstructure of a submarine boat.

Located interiorly of the hull is a torpedo-handling compartment 5 which may be one of the living or operating compartments of the vessel or may itself be a torpedo-storage compartment. Beneath it, in the embodiment illustrated, is a torpedo-storage compartment 6. The floor or deck 7 forms a partition between compartments 5 and 6, and this floor or deck will have the necessary hatch (not shown) for passing the torpedoes from compartment 5 to compartment 6. A track 8 is mounted on floor 7, and a truck 9 is provided for riding upon said track as hereinafter described.

A vestibule or minor compartment 10 is located above the compartment 5 to permit ingress and egress of torpedoes 11 relatively of the compartment 5; a tackle 12 being disclosed to facilitate an employment of minor compartment 10 in accordance with the present invention.

At the top of the minor compartment 10 is provided a circular hatch 13 equipped with a cover adapted when desired to be adjusted to make a water-tight closure for said hatch. Between the minor compartment 10 and the compartment 5 there is provided an elongated hatch 14 equipped with a cover adapted when desired to make a spray-tight closure for hatch 14.

The minor compartment 10, it will be

noted, if constructed as in Figs. 1 and 2, may have its side walls 10 placed very close together (Fig. 2) the distance between these parallel walls, and also the diameter of the circular hatch 13 and the maximum lateral dimension of hatch 14, being very slightly greater than the maximum diameter of a torpedo 11. With the minor compartment so constructed, the space inclosed by it, and consequently its buoyancy, is small. Aside from the mere economy of space, this is of great importance if the minor compartment be arranged, as shown, as a water-tight chamber above the hull 3 and located within 10 the space between the hull and the superstructure 4, since it is important to confine within definite limits the buoyancy above the hull line of the vessel.

To remove from the hull of a mother-submarine one of the torpedoes located in compartment 5, it is necessary first to open both the hatches 13 and 14. Preferably the torpedoes will be arranged horizontally and side by side within the storage compartment, and with their propeller-ends all pointing the same way as indicated. The track 8 and truck 9 need not be present, but such a track and truck are useful for the purpose hereinafter described.

Without such track and truck a torpedo could be removed from the hull interior by means of the tackle 12; in which case the hook end of the tackle would be brought through hatches 13 and 14 and into the interior of main compartment 5 and, after a suitable slackening of the tackle, said hook end would be engaged as shown with the propeller end of a torpedo; whereupon a hoisting of the tackle would slide the opposite end of the torpedo over the upper surface of deck or floor 7 until said torpedo assumes, first the location indicated in broken lines at 11', next, the location indicated in broken lines at 11'', next, the location indicated in broken lines at 11^a and, finally, a suspended disposition clear of the mother-submarine. If, however, the track 8 and truck 9 be used, the torpedo would be laid thereon as shown in full lines, the hook-end of the tackle 12 would be attached to the propeller-end of said torpedo and the torpedo would be withdrawn as indicated by the broken lines at 9', 11', 11'' and 11^a as above described.

The value of the above described construction for the purpose of taking aboard the mother-submarine a stock of torpedoes is self-evident. If the track 8 and truck 9 be employed, it will be observed that the tendency of the said truck (after being brought to the location 9') to travel by gravity toward the full line location of the truck, on account of the slope of said track, is important. Before the torpedo is lowered 60 into the hull of the mother-submarine the

truck is brought to its said broken-line location. It is there temporarily held in some manner until the incoming torpedo is lowered to about the location 11'', whereupon the torpedo is swung, say manually, to take 70 up the location 11', with its end resting on the truck, after which, and upon the release of the truck and a slackening of tackle 12, the truck travels by gravity to its full line 75 location and disposes the torpedo horizontally with its propeller end below circular hatch 13, and so that said torpedo may readily be removed from the track and truck and placed in storage.

I claim:—

1. In a submarine boat, the combination of a hull having a main compartment therein for the accommodation of torpedoes, a superstructure on the hull, and a water-tight vestibule compartment extending from the hull to the top of the superstructure and communicating at its lower end with the hull and its upper end with the space above the superstructure, said compartment being of uniform width throughout and of decreasing length in the fore and aft direction from the bottom thereof to the top, whereby a torpedo lowered may be turned from a vertical position toward a horizontal position while it is being lowered through the 95 vestibule and into the hull.

2. In a submarine boat, the combination of a hull having a main compartment therein for the accommodation of torpedoes, a non-water-tight superstructure on the hull, a water-tight vestibule compartment extending from the hull to the top of the superstructure, a closure for the passage from the vestibule to the hull which is elongated in the direction of the length of the boat, and a closure for an opening in the upper end of the vestibule compartment, said compartment being of substantially uniform width throughout and of decreasing length from the bottom to the top, whereby a torpedo 100 may be turned from the vertical position toward the horizontal position while being lowered through the vestibule.

3. In a submarine boat, the combination with a hull having a main compartment therein for the accommodation of torpedoes, of a non-buoyant super-structure on said hull, and a water-tight vestibule compartment extending from the hull to the top of the superstructure, said compartment being 115 upwardly tapering, with a substantially vertical axis, and having at its upper extremity a circular hatch with a circular water-tight hatch cover therefor, and at its lower extremity an elongated hatch opening into the 120 torpedo compartment; substantially as described.

4. In a submarine boat, in combination with the hull, an elongated main compartment therein for the accommodation of tor- 130

pedoes, a minor compartment located above the main compartment, an elongated hatch to provide a communication between the main and minor compartments, and a circular hatch located in the upper portion of the minor compartment and above one end of the elongated hatch, said minor compartment tapering upwardly toward said circular hatch from a point above said elongated hatch.

5. In a submarine boat, in combination with the hull, an elongated main compartment therein for the accommodation of torpedoes, a minor compartment located above the main compartment adjacent to one end thereof, the minor compartment tapering upwardly and having a substantially vertical axis, and a trackway in the main compartment below the minor compartment and arranged for receiving an end of a torpedo being lowered substantially vertically through the minor compartment, the taper of the minor compartment, the height of the main compartment and the line of extension of the trackway being so calculated and arranged that the said end of the torpedo may be moved along the trackway to guide the torpedo to pass through the minor com-

partment while tilting the torpedo from the vertical toward the horizontal.

6. In a submarine boat, in combination with the hull, an elongated main compartment therein for the accommodation of torpedoes, a minor compartment located above the main compartment adjacent to one end thereof, the minor compartment tapering upwardly and having a substantially vertical axis so that a torpedo may be tilted from the vertical toward the horizontal while being lowered through the minor compartment, a trackway in the major compartment below the minor compartment comprising a rail arranged lengthwise with the major compartment and sloping downwardly from a point below the minor compartment, and anti-friction means movable on the track and formed to receive and support an end of a torpedo which is being lowered through the minor compartment, whereby gravity acts to move the torpedo along the rail while the torpedo is being passed through the minor compartment and tilted from the vertical toward the horizontal.

In testimony whereof I affix my signature.

LAWRENCE Y. SPEAR.
